UNITED STATES PATENT OFFICE.

WILLIAM RICHARDS, OF ROCHESTER, NEW YORK.

CLOTHES-PIN.

SPECIFICATION forming part of Letters Patent No. 443,602, dated December 30, 1890.

Application filed June 19, 1889. Serial No. 314,791. (No model.)

To all whom it may concern:

Be it known that I, WILLIAM RICHARDS, of Rochester, in the county of Monroe and State of New York, have invented a certain new and useful Improvement in Clothes-Pins; and I do hereby declare that the following is a full, clear, and exact description of the same, reference being had to the drawings accompanying this specification.

10 My improvement relates to that class of clothes-pins in which the jaws are held together by a spring-wire and a hook is used to suspend the pin on the line.

15 The invention consists in the construction and arrangement of parts hereinafter described and claimed.

In the drawings, Figure 1 is a front elevation of my improved clothes-pin. Fig. 2 is an edge elevation of the same. Fig. 3 is a 20 rear elevation. Fig. 4 is a cross-section in line $\alpha\alpha$ of Fig. 2. Fig. 5 is an edge elevation similar to Fig. 2, but showing a modification.

25 A' indicate the two jaws, which are preferably made of wood of the form shown and turning on a center pivot or bearing a . This pivot consists of a piece of wire with its ends bent, forming short claws b , which are driven into the wood of one of the jaws, and the other jaw is formed with a groove c , which 30 fits loosely over the rounded side of the pivot. The clamping-spring hereinafter described holds the jaws together, and a loose joint is thus produced, which is as effective as a tight pivot, while considerable expense is thus 35 saved in the construction.

40 B indicates the clamping-spring. It is made from a single length of spring-wire of suitable size. The two ends start from the point d , where they are united by a clasp f of sheet metal or other means. Thence they extend upward on the face of the clothes-pin, 45 forming the line-clamp g , which catches over the suspending cord or wire C . At the top a coil h is formed on each side, which gives increased elasticity; but, if desired, the wire may be formed without any coils at this point, as shown in the modification, Fig. 5. Thence the two sides of the wire pass inward transversely across lugs i , formed at 50 the top of the front jaw A , as shown at k , and thence they turn down and extend longitudinally on the outer face of the jaw, resting

in a cavity l , as shown at m . Thence they cross the two jaws to the back side below the pivot, being formed with side coils n , which 55 rest against the edges of both jaws. Thence they extend down longitudinally on each side of the back, as shown at o , and finally they cross the back, as shown at p , completing the 60 circuit. This spring-wire serves several different purposes. First, it clamps the two jaws together, so that they always remain in contact at the pivotal point whether the jaws are open or closed; second, they clamp the two lower 65 ends of the jaws together to hold the cloth, this clamping action being produced by the two opposing cross-lengths on opposite faces of the clothes-pin below the pivot; third, the side coils n at the edges inclose the jaws and keep them in alignment at all times and 70 prevent lateral displacement; fourth, the front lengths g form an open clamp, which can be hooked upon the supporting wire or cord C . It is obvious that the construction of the clamping-wire can be modified more or less 75 without departing from the invention. For instance, a greater or less number of the spring-coils can be used, and they may be located at any desired point.

80 In use the clothes-pins are attached to the clothes before the clothes are hung out. This is done by clamping them on the clothes at intervals and may be done in the house. The clothes are then carried out and hung on the line. They are attached to the line by simply 85 hooking the clamp g over the line, as shown in Fig. 2. This clamp hugs the line closely and holds the clothes in place. It prevents any contact of the clothes with the line, and therefore soiling by contact with the line and 90 difficulty of removal therefrom are avoided. It is of especial advantage in winter, as it obviates the freezing of the clothes to the line and the danger of tearing in removal of the clothes. It also insures comfort, as but little 95 time is required to hang out or take in the clothes, as the pins can be applied or removed in the house, and the simple work of hanging to or removing from the line is only required out of doors.

100 The lower clamping ends of the jaws may be constructed in any desired manner. Fig. 2 shows a single corrugation r , and Fig. 5 several of such corrugations.

Having described my invention, I do not claim, broadly, a spring clamping wire nor a hook by which to suspend the clothes-pin to the line.

5 What I claim as new, and desire to secure by Letters Patent, is—

1. The combination, with the pivoted jaws A A', of the spring clamping wire B, embracing the jaws below the pivot, constructed with 10 lengths m m, which extend to the top of the jaw A and around lugs i i, and the outside return-lengths g g, extending down outside the jaw and forming a double-sided clamp for hooking on the line, as herein shown and described.

15 2. The combination, with the jaws A A', of

the spring clamping wire B, embracing the jaws below the pivot, constructed with side coils n n, embracing the sides of both jaws, and thereby preventing lateral displacement, 20 the lengths m m, extending to the top of the jaw A, and the return-lengths g g, forming a double-sided clamp for hooking on the line, as herein shown and described.

In witness whereof I have hereunto signed 25 my name in the presence of two subscribing witnesses.

WILLIAM RICHARDS.
